[57] ABSTRACT

Gases are admitted and exhausted by ports in a sleeve around a piston. The sleeve is actuated from a point on the piston rod, giving it roughly an elliptical motion, favorable for keeping ports open a long time for entrance and exit of necessary quantum of gases without throttling.

RELATED INVENTIONS

There is a related invention (by me) applied for in Holland, but withdrawn before publication.

BACKGROUND OF THE INVENTION

The prime problem in piston and cylinder expansion motors is the weight per H.P. Up to now that weight per H.P. is so high that these motors have no commercial meaning. The remedy is to let the motor operate with high piston velocity (30-35 Mts/sec), defined by $2 L N/\omega$ where L is stroke in M/sec, N=RPM.

The consequences of a high piston velocity is always throttling of the gases, unless sufficient port opening is provided to prevent it. The actuation of the sleeve is such that the ports in it keep open for a sufficient time to allow a great gas weight to enter or exit the cylinder for high H.P. production without throttling. That is the field of the invention.

PRIOR ART

There have been a great many piston and cylinder expansion engines made in bygone years, all slow moving with low piston velocity. The power developed was equal or a little more than the friction.

About 1914 a Belgian company named "Minerva" fabricated an I.C. automobile motor with two sleeves. Harry R. Ricardo in his book "The High Speed I.C. Engine" Blackie & Sons London 1931 describes sleeves but none of them can do what my motor can, viz: keep the ports open long enough to allow a great gas weight to enter and exit the cylinder without throttling.

SUMMARY OF THE INVENTION

Although the summary may be studied also in the "Preferred Embodiment" the essence is set forth in this summary, and pictured in FIG. 1. The movement of the sleeve is derived from a sphere with center P., attached to the piston rod, as can be seen on FIG. 1, sections a, b, c, d, are cross sections across the longitudinal section on the left.

P describes in general an ellipse, but it is experimentally found that this ellipse produces exceptional results only when it is placed in the spot shown in the drawing where

stroke of piston V-T— 38 millimeter

length of piston rod — 75 millimeter

distance P to Q — 18 millimeter

distance P to top of crank circle — 22 millimeter or multiples or fractions of it. P is in what may be called a "preferred" neighborhood. The ellipse may be computed accurately and is shown. Q, R, S are the positions of P when the crank is in T, U, & V. The ellipse should have a crown as flat as possible, this is enhanced by offsetting the crank axis a slight distance from the piston axis.

The sleeve is moved by a hinge with vertical axis, there are 2 hinge supports 1 & 2, attached to elongation 3 of sleeve 4. The hinges are represented in the direction of arrow 5, supposed that this elongation were transparent. The link whereby the movement of P is transferred to the hinge supports is divided in 2 halves.

6p & 6q, the link is split along a - P. They are united by bolt 7, then rotated on P until the blades 8, 9 & 10 slip between 1 & 2 then the final central bolt 12 is in-

serted. Now the sphere P forces the sleeve to oscillate back and forth, FIG. 1, b represents the position of 3 when P is in Q and the crankpin in T, c when P is in S, the crankpin in V. The sleeve thus describes an ellipse, deflected from the ellipse described by P. The essential part is that the sleeve and the openings in it admitting the gas are stationary in a vertical sense during a large part of the descent of the piston thus providing ample opening to charge the incoming gas into the cylinder without throttling.

BRIEF DESCRIPTION OF THE DRAWING (FIG. 2)

The motor consists of a piston 20, a connecting rod 21 and crank 23, which is of the overhanging type. Around the piston can move the sleeve 24, therein are the openings 29 for admission and outlet of the gas after expansion. The sleeve moves in housing 25 with the inlet 26 and outlet 27 nozzle. The sleeve is so long that in its lowest position there is enough dam left above the lower edge of the cover 28. The actuation of the sleeve actuated by spherical knob, link and hinge is described in "summary of the invention".

DESCRIPTION OF PREFERRED EMBODIMENT (FIG. 2)

After the brief description above and the summary of the invention hardly any more explanation is necessary. See FIG. 1 and 2. The piston-cylinder expansion engine meant by this invention contains necessarily a piston 2, a sleeve 24, a connecting rod 21 and crank 23 which is the overhanging type. Sleeve 24 is provided with 4 openings 29 for inlet and outlet. The vital parts are housed in housing 25. A gas expansion motor in general is only viable when enough gas weight can be introduced in the cylinder that is: when enough opening is available to let the gases pass without throttling. To be viable, the gas expansion motor must operate with high piston velocities above 30 M/sec. Throttling will certainly occur when no great openings are provided. This is accomplished by the sleeve mechanism already described in the "Summary". Whilst the piston descends, the sleeve and openings do not. FIG. 1 shows the piston in top, the sleeve openings 29 are visible they correspond with openings in the circular admission ring 30. The crank rotates 45°, this makes the piston descend 12 percent of her stroke. Whilst the sleeve provides full openings, it keeps vertically stationary. On revolving further the ports close by the descending sleeve, but the overall result is that considerable gas weight enters the piston without throttling.

The outlet is analogous, when the crankpin is in W1, the sphere is in Z, resp Z1. The piston has travelled 85 percent of her stroke, the top has descended to W2 the lower edge of opening 29 is just about allowing the gases to escape. Rotating further the crank arrives in W3, the piston top in W4. The piston top is just about going to exhaust. Now compression starts, depending on the exhaust pressure. It ends exactly in point 31 of the indicator diagram of FIG. 3. For high exhaust pressure it might be necessary to make an extension to close later, this is detail. Now the revolution is completed.

I claim:

1. A combustion engine including a cylinder, a crank shaft, a connecting rod journaled on to said crank shaft, a piston attached to said connecting rod and recipro-

cating by means of said crank shaft and said connecting rod within said cylinder, and a cylindrical sleeve valve having inlet and outlet ports, said sleeve valve being mounted concentric with respect to both said piston and said cylinder, and a connecting link for actuation of said sleeve valve with both a rotative and a reciprocative motion, said connecting link having one end connected to said sleeve valve and another end connected to said connecting rod.

2. A combustion engine as claimed in claim 1, wherein the connection of said another end of said connecting link to said connecting rod is effected by means of a spherical ball attached to said connecting rod, said ball being mounted in the said another end of said con-

necting link.

3. A combustion engine as claimed in claim 2, wherein said connecting link is separated along its length into two sections, said two sections being normally held together by a bolt and cooperating, when bolted together to enclose and form a swivel mount for said ball at said another end of said connecting link, said one end of said connecting link forming one part of a hinge joint, another part of said hinge joint being connected to said sleeve, and a hole through said one part and said another part of the said hinge joint, said one part and said another part being held together for swivel motion by a second bolt through the said hole.
